UNITED STATES PATENT OFFICE.

EMIL STANECKY AND LEA H. STANECKY, OF CHICAGO, ILLINOIS.

WINDOW.

1,113,502.

Specification of Letters Patent.

Patented Oct. 13, 1914.

Application filed April 10, 1912. Serial No. 689,935.

To all whom it may concern:

Be it known that we, EMIL STANECKY and LEA H. STANECKY, citizens of the United States, and residents of the city of Chicago, county of Cook, and State of Illinois, have invented certain new and useful Improvements in Windows, of which the following is a specification.

Our invention relates to improvements in windows having inwardly swinging sashes, and has for its object the provision of an improved hinge construction for permitting of such inward swinging of the window sash.

15 The invention consists in the combination and arrangement of parts hereinafter described and claimed.

The invention will be best understood by reference to the accompanying drawing 20 forming a part of this specification, and in which—

Figure 1 is an interior elevation of the lower portion of a window embodying our invention, Fig. 2, an enlarged sectional view 25 showing one of the hinges in position of use, Fig. 3, a face view of the hinge, Fig. 4, a rear view of a modified form of hinge, Fig. 5, a front view of the construction illustrated in Fig. 4, and Fig. 6, a section taken 30 on line 6—6 of Fig. 5.

The preferred form of construction as illustrated in the drawing comprises a window sash 7 mounted in the usual frame, the outer side 8 of the lower portion of one of 35 the guide grooves for said sash being removed to permit of inward swinging thereof and said sash being provided with a suitable lock 9 to prevent such inward swinging when desired. Hinge studs 10 are secured to sash 7 near its top and bottom on the side opposite to said removed portion. 40 Downwardly swinging foldable socket members 11 are arranged in casings 12 mortised into the window frame, said socket members 45 being adapted to receive hinged studs 10 when sash 7 is lowered to its bottommost position. A stop 10' is provided on the lower sash in position to engage the corresponding lower socket member upon elevation 50 of the sash to swing said socket member upwardly into folded position. A spring 13 is also provided in casing 12 and bearing against socket member 11 to hold said socket member in either of its positions. It will

be observed that the lowermost stud 10 is arranged in the path of the uppermost socket member so that when sash 7 is fully raised, the lowermost stud 10 strikes the upper socket member 11 and automatically folds it into inoperative position.

In Figs. 4, 5 and 6 we have illustrated a modified form of hinge member. This construction comprises a casing 14 secured to the window frame in proper position and carrying a socket member 15 which is secured to a trunnion 16 mounted in casing 14 as shown. At its inner end trunnion 16 carries a plate 17 which in turn carries a crank pin 18 which is connected by means of a spring 19 with a pin 20 in casing 14. 65 A stop pin 21 serves to limit the downward swing of socket member 15. This furnishes a simple and efficient form of socket member.

While we have illustrated and described 70 the preferred forms of construction for carrying our invention into effect, these are capable of variation and modification without departing from the spirit of the invention. We, therefore, do not wish to be 75 limited to the precise details of construction set forth, but desire to avail ourselves of such variations and modifications as come within the scope of the appended claim.

Having described our invention what we 80 claim as new and desire to secure by Letters Patent is.

A window construction comprising a frame; a sash slidably and swingingly mounted in said frame; a hinge member 90 carried by said sash; a hinge member pivoted in said frame and arranged to co-operate with said first mentioned hinge member; and a stop on said sash located below the hinge member thereon and arranged to 95 engage the hinge member on said frame and fold it into inoperative position upon elevation of said sash, substantially as described.

In testimony whereof we have signed our 100 names to this specification in the presence of two subscribing witnesses.

EMIL STANECKY.
LEA H. STANECKY.
